COMBINATION PLUMBING FIXTURE

Arthur H. Zimmerman, Hammond, Ind.

Application June 9, 1934, Serial No. 729,803

18 Claims. (Cl. 4-2)

This invention relates to a combination plumbing fixture, and is more particularly directed to a bathroom fixture comprising a bathtub, water closet and lavatory ensemble or unit.

In the ordinary bathroom as now designed, the bathtub, water closet and lavatory are separate units, each independently and separately mounted and supported, with individual piping connections to each unit. Thus, the lavatory is provided with hot and cold water connections and also a waste connection, and since it is of considerable weight, is also ordinarily provided with supporting legs or a standard which is secured to the floor of the bathroom, since ordinarily the weight of such a structure is not capable of being supported upon the wall. The water closet is provided with a flushing connection and a waste connection, which must be led through either the wall or floor, and means must also be provided for firmly supporting the device upon the floor in upright fixed position.

These piping and supporting means render it extremely difficult to maintain the bathroom in the desired clean and sanitary condition, since it is practically impossible to maintain the floor and wall clean above the water closet and the lavatory. Further, the visible piping connections which project through the wall or floor are both unsightly and unsanitary, since they provide a plurality of surfaces for catching and retaining dirt, dust and the like. In addition, the use of such individual units requires cutting up of the floor and floor joints, and produces an obstructed floor which is hard to maintain clean.

It is an object of the present invention to provide an ensemble unit comprising a bathtub, water closet and lavatory, the closet and lavatory being mounted upon the front face of the tub, whereby the unit is easy to maintain clean, occupies little space, and provides a compact, neat appearing installation which does not obstruct the floor or walls of the bathroom, and consequently the cleaning and maintenance of a neat and sanitary bathroom is facilitated. Furthermore, all water and waste piping is concealed, with no piping projecting through the walls or floor, which eliminates the unsightly appearance of prior types of bathroom fixtures of which I am aware.

The preferred embodiment of the present invention provides a bathtub structure having a front panel or wall upon which is mounted, by means of integrally flanged curved brackets or pedestals, the water closet and lavatory, thus requiring no floor supports for these structures,

since they are supported in raised position off of the floor and upon the face of the tub. The water connections are all disposed rearwardly of the front panel or face of the tub, entering directly into the water closet or lavatory through the tub panel, whereby they do not project through the walls or floor of the bathroom, and are completely out of sight.

In prior installations of which I am aware, the "roughing in" operations for connecting the piping to the various fixtures was complicated, and required from four to five feet of wall space. By the present construction, these operations are considerably simplified, and the wall space required is therefore reduced approximately 50%.

The present invention provides an ensemble which is adapted for either right or left hand corner tub construction, in which the tub is secured in a corner of the room, and has an end and side wall projecting free from the walls of the bathroom, or for a recess type of tub construction, which latter case only the front face of the tub is open, the remaining sides engaging the walls of the recess. The tub and the fixtures may be provided with any desired type of design and color combination, and the lavatory may be made of vitreous china or enameled iron, as desired. The closet can be of any preferred type, such as a wash-down, siphon-jet, or blow-down type. The supply connections for the fixtures are easily accessible from the panel at the side of the tub for installation, inspection, repair or replacement.

One feature of the present invention is the provision of a plumbing fixture by which the venting means for the tub, lavatory and water closet are all combined in a single vent, which eliminates to a considerable extent the piping required in the present construction.

A further feature of the invention is the provision of waste pipes for the water-closet and lavatory which are provided with oppositely threaded ends, so that rotation of the pipe during assembly or installation secures it simultaneously in position at both ends.

In some municipalities, a horizontal run of waste pipe of over three or four feet from a vent is prohibited, and in such instances the present construction is so designed that an anti-siphon type of lavatory trap may be employed. In this connection, the lavatory and water-closet are interchangeable in position with respect to the tub, so that the water-closet may always be placed in proximity to that end of the tub which is adjacent the waste riser connection.

In order to provide for uniformity of construc-

tion, the panel of the tube is provided with spaced sets of cut-out openings, each set being capable of accommodating either the water-closet or lavatory. Since the water-closet does not require the openings necessary for the faucet connections of the lavatory, and the lavatory does not require the flush valve opening required by the water-closet, these openings are suitably closed by ornamental fittings when not in use. The two ends of the tub proper are also provided with corresponding sets of openings for faucet connections, the unused set of openings being covered by a suitable ornamental fitting, such as a soap dish or the like.

In order to provide for rapid and simplified assembly of the unit, I provide a manifold having two chambers, one connected to a source of hot water supply, and the other connected to a source of cold water supply. From these chambers, suitable flexible conduits, such as copper tubing or the like, are led to the various faucet connections and to the flush valve connection for the water-closet. This provides for ready installation of these connections with a minimum amount of labor.

Other objects and advantages of the present invention will appear more fully from the following detailed description, which, taken in connection with the accompanying drawings, will disclose to those skilled in the art the particular construction and operation of a preferred form of the present invention.

In the drawings:

Figure 1 is an elevational front view of a tub, water-closet and lavatory ensemble as provided by the present invention, shown in connection with the vent and waste fittings;

Figure 2 is a plan view of the ensemble construction shown in Figure 1;

Figure 3 is an end elevational view of the ensemble construction shown in Figures 1 and 2;

Figure 4 is a perspective detail view of a modified form of tub construction, prior to its assembly in the ensemble unit;

Figure 5 is a vertical sectional view of the tub construction shown in Figure 4;

Figure 6 is a vertical sectional view of a lavatory, shown as connected into the ensemble construction of the present invention;

Figure 7 is a sectional view taken substantially on the line 7—7 of Figure 1, showing the manner in which the waste pipe connection is roughed into the tub panel;

Figure 8 is a sectional view taken substantially on the line 8—8 of Figure 7, showing another detail of the roughing in construction;

Figure 9 is a front elevational view of a modified construction; and

Figure 10 is an end view of an ornamental fitting for covering certain of the unused openings of the construction shown in Figure 9.

Referring now in detail to the embodiment of the invention shown in Figures 1, 2 and 3, I have provided a tub, indicated at 12, which is provided with the recess portion 13 comprising the water receiving portion of the tub, and is also provided with the front panel or face 14, which may, if desired, be recessed or beveled, as indicated at 15, to provide a suitable design or the like thereon.

Secured to the front face of the tub is a lavatory indicated generally at 16, provided with a wash bowl or basin 17, and also provided with an extending pedestal or supporting portion 18, which terminates in a flanged bracket surface 19 extending normal to the plane of the lavatory 16.

and provided with a pair of threaded bolt members 20 adapted to thread into the front face 14 of the tub, the metal of the tub being preferably thickened at this point, as indicated at 21, to provide an adequate support for the pedestal. The lavatory 16 is also provided, as shown in Figure 6, with an inner extending flange portion 23, which is bolted, by means of bolts 24, to the upper surface of rim 25 of the tub, there preferably being several of such bolt connections disposed on opposite sides of the center of the lavatory.

Extending centrally between the bolted portions 23 of the lavatory are the flexible water connections 26 and 27 extending to the faucet fixtures 28 of the lavatory, these connections passing through an opening 29 formed in the rim 25 of the tub. Preferably, the cold water connection is indicated at 26, the hot water connection being shown at 27, and these connections are extended into a valved housing member 29 secured to the under-surface of the upper rim of the lavatory 16, and controlled by the faucet members 32 and 33. The faucet itself is indicated at 34, being directed into the bowl 17. The fixture 28 is also provided with the operating member 35 which controls the stopper means 36 mounted in the drain 37 of the basin 17.

The drain 37 is connected through the pipe 38, anti-syphon trap 39 and pipe 40 to a waste connection elbow 42, the pipe 40 being connected to the waste connection through the opening 43 in the front panel of the wall 14. The pedestal or bracket 18 is provided with an opening 44 which permits access to anti-syphon trap 39, in order to permit inspection, removal and cleaning of the same.

Secured in spaced relation to the lavatory 16, and mounted upon the front face or panel 14 of the tub 12, is a water closet indicated generally at 50, which water closet may be of any standard type, such as a siphon-jet operating closet, or a wash-down or blow-down type. The closet 50 has the depending portion 51 provided with an annular flange 52, which flange is bolted or otherwise suitably secured to the front face 14 of the tub by means of bolts 53 disposed on opposite sides thereof. The closet seat is indicated at 54, and is provided with a cover 55 hinged as shown at 56, in the ordinary manner. A suitable flush valve, shown at 57, is extended through the wall 14, and controls the flushing action of the water-closet 50. The interior of the depending portion 51 of the bowl 50 is connected, through an angle or elbow 58, to an intermediate waste pipe 59, the member 58 being adjustable in position as shown in detail in Figures 7 and 8 to accommodate roughing in of the same.

Considering now Figures 7 and 8, the interior of the bowl 50 and depending portion 51 thereof is connected, through the conduit or outlet 60, to the elbow 58, the elbow 58 being provided with a cylindrically flanged portion 62 having a beveled edge 63. The rear face of the wall 14 is provided with a pair of angularly extending dovetail portions 64, which are spaced apart a distance equal to the diameter of the flanged portion 62 of the elbow 58, and the elbow 58 is adapted to have relative movement longitudinally of the members 64 while the waste pipe 59 is being connected thereto, to accommodate roughing in of the pipe.

The tube itself is provided with a faucet 65, connected through the fixture 66 to a pair of water supply pipes 67 and 68, as shown in Figure 2. 75

The pipe 67 is preferably adapted to provide a cold water supply for the faucet 85, while the pipe 68 provides a hot water supply therefor. The relative quantities of water admitted to the faucet 85 from the pipes 67 and 68 are controlled by the corresponding valve members 69 and 70.

In providing the hot and cold water connections for the lavatory 16 and the tub 12, I preferably provide a manifold indicated at 72, which has a cold water chamber 73 and a hot water chamber 74, the two chambers being preferably separated by an insulating member for preventing transmission of heat therebetween. The cold water chamber 73 is connected, through valve 75, to a cold water supply pipe 76, while the hot water chamber 74 is connected, by means of valve 77, to a hot water supply pipe 78. From the cold water supply chamber 73, flexible connections, comprising copper tubing or the like, are led off to the tub and lavatory, comprising the connections 67 and 26, respectively. Similarly, the pipes 68 and 27, for supplying hot water to the tub and lavatory, respectively, are connected on the hot water side of the manifold 72, that is, to the chamber 74. The connection 79, leading to the flush valve 80 controlled by the valve member 57, is connected to the manifold 72, and from the flush valve chamber 80 is connected through the member 82 to the water-closet 50, as is well known.

The tube 12 is provided with a drain 83, which is connected to a suitable drum trap 84 by means of an over-flow riser 85 positioned beneath the rim of the tub and extending vertically upward with respect thereto. From the drum trap 84, the waste pipe 86 connects the drain to the common waste line 81.

A waste riser for the building is indicated generally by the numeral 90, and is provided with the usual unvented T member or fitting 92, to which is connected the waste pipe 87, which preferably extends at a slight angle to the horizontal, sloping toward the drain or riser 90. In older buildings, in which a waste stack is already in place outwardly of the tub, the waste connection 27 may be extended outwardly to the stack. The waste pipe 87 is adapted to receive the waste from the tub through the drum trap 84, and the waste from the lavatory 16 through the waste pipe 93 connected to the elbow 42 which communicates with the waste pipe 40 of the lavatory, which waste pipe 93 is connected into a second T 94 disposed at a higher level than the T 92. The waste from the water-closet 50 passes through the pipe 59 to the end elbow member 95, which has the offset connection 96 for receiving waste from the T connection 94 connected to the lavatory waste pipe 93. Extending upwardly from the T connection 94 is a vent pipe 97, which is set into the upper connection 98 of the T 94, and at its opposite end is threaded into a triple elbow fitting 99. The vent for the water-closet 50 comprises the extending bell fitting or slip hub 100, receiving the lower end of a vent pipe 101 which is threaded at its upper end into the fitting 99. The vent for the tub waste pipe 86 comprises the fitting or slip hub 102, which receives the lower end of the vent pipe 103 threaded at its upper end into the fitting 99. The elbow 99 is connected through pipe 104, to a second waste riser T 105 connected to the waste riser 90. Thus it will be seen that the vent means for the tub, lavatory and water-closet are combined into a single vent 104 leading to the waste riser.

The assembly of the pipes 97, 101 and 103 within their corresponding fittings at the lower

ends thereof is in the usual manner, the pipes being dropped into the fittings, and then slightly raised as they are threaded at their upper ends into fitting 99. The space between the outer surface of the pipes and the inner periphery of the bell is then caulked and filled with suitable sealing material, such as lead or the like. Similarly, the connections between the fittings 92 and the riser 90, and the connections between the member 94 and the elbow 99 are completed in the same manner.

It is to be noted that the waste pipes 39 and 93 are threaded in opposite directions at the ends thereof, so that when mounted into position, rotation of the pipe will result in threading of the same at both ends thereof, thus requiring only a single operation to complete the connection of the pipe at both of its ends. During this rotation, the beveled flanged portions of the elbows 42 and 58 are moved longitudinally of the locking dovetail strips 64 as shown in Figures 7 and 8, and the required roughing in operation is easily accommodated by means of this construction.

It is thus apparent that all of the piping connections for both the lavatory and water-closet, as well as for the tub, are concealed from view behind the front wall 14 of the tub, and extend between this wall and the recess portion 13 of the tub proper, beneath the upper rim 25 of the tub. As shown in Figure 1, the tub 12 is of the recess type, being adapted to fit between walls 106 and 107 which are diagrammatically indicated in this figure. With a corner type of tub, in which one end thereof is exposed as well as the front face, the same construction can be employed without any difficulty.

By the provision of flexible tubing for the conduits 26, 27, 67, 68 and 79, it is possible to facilitate the connection of these members within the relatively small space provided, since they may be bent into the desired angles and readily connected. Further, by the provision of the trap 39, which is easily accessible through the opening 44, and the provision of the trap 84 which is accessible from the end of the tub, it is possible to maintain the waste line for the tub and lavatory in proper condition at all times. By reason of the trap 84, it is impossible for the waste from either the water-closet or the lavatory to back up into the drain for the tub. Similarly, by providing the entrance of the pipe 93 at a point above the waste pipe 59, the waste from the water-closet cannot back up into the lavatory 16. Thus, the present construction prevents backing up of the waste lines for any of the units comprising the ensemble, and also provides a common vent for all three of the waste lines.

Referring now to the structure shown in Figures 4 and 5, a tub member is indicated at 110, provided with the recessed portion 112 defining the tub proper, and provided with a horizontally extending rim portion indicated generally at 113. Integrally formed supporting webs or flanges 114 and 115 are provided for spacing the tub with respect to the floor, these reinforced webs serving to support the tub in fixed position. The front face of the tub comprises the planar surface 116, which is formed integrally with the rim 113, and which extends down to the floor level. The member 110 may be formed of enameled iron or the like. On opposite ends of the member, openings are provided, as indicated at 117 and 117, for receiving the faucet connection, shown in Figure 5 by the reference numeral 118. This faucet connection includes the faucet 119 opening 75

into the tub portion 112, and also includes the connections, such as described in connection with the previous embodiment, of the hot and cold water supply pipes. The overflow member 120 is disposed beneath the rim of the tub, and in line with the faucet fixture 118.

If the tub is a right end connected tub, the opening 117' will be used for the faucet fixture connection, while if for a left hand connected tub, the opening 117 will be employed, as shown in Figure 5. When a left hand connected tub is employed, the opening 117' may be covered by an ornamental fitting, such as a soap dish 122 or the like.

15 The rim 113 is provided with two sets of openings, indicated generally by reference numerals 123 and 124. These openings correspond to the opening 29' and the bolt openings for the bolts 24 as shown in Figure 6, to provide for connection of the hot and cold water supply pipes to the lavatory faucet fixture 28, and to provide threaded openings for receiving the supporting bolts 24. However, when the lavatory is positioned over the openings 123, the openings 124 would 20 ordinarily be exposed.

In order to enhance the appearance of the tub, I have provided, as shown in Figures 9 and 10, means for covering these openings, comprising the ornamental fitting 125, which is provided 25 with supporting bolt members 126 secured in the two outside openings of the set of openings 123, and with a central dummy member 127 covering the central one of the set of openings. The member 125 may be provided with bumpers 128, 30 adapted to engage the rear surface of the water-closet seat cover 55 when the same is raised in position, since the water-closet will be positioned in alignment with the unused set of openings 123 or 124.

40 In the front face or wall of the tub I provide two sets of spaced openings, comprising main openings 130 and 130', flush valve openings 132 and 132', drain or waste openings for the lavatory indicated at 133 and 133', and supporting 45 threaded bolt openings 134 and 134' so that when the lavatory and water closet are disposed in the manner shown in Figure 9, the waste opening from the bowl 50' of the water-closet will extend through opening 130, by means of an outlet member such as member 60, to be connected by means 50 of elbow 58 to the waste pipe 59 communicating with the main waste pipe 87. Similarly, the threaded openings 134 will receive the supporting bolts 140, as shown in Figure 9, the bracket portion of the water-closet in this instance being 55 made of greater lateral extent than the bracket 52 of Figure 1, in order to provide a larger bearing and supporting surface therefor. The opening 132 in this particular embodiment will then receive a flush valve such as the valve 57, and the opening 133 will provide an inlet for the flushing water to the water-closet.

60 Similarly, the opening 130' will be covered by the lower end of the bracket or pedestal 18' of the lavatory 16', the opening 133' will receive the drain pipe 40 and elbow 42, the openings 134' will receive the attaching bolts 20' and the opening 132 will receive an ornamental closure fitting 142. If the lavatory 16' and the water-closet 50' are reversed, the connections will be correspondingly reversed as is apparent from the drawings. By the provision of the two sets of openings in the front wall 116, the two sets of openings in the rim 113, comprising the openings 123 and 124, and the two end openings 117 and 117' the

tub is adapted either for right or left hand connection, and also, is adapted to support the water-closet and lavatory in either of the two positions, depending upon which end the water connections are provided. The tub 112 is provided with a 5 drain 143 extending through an opening in the supporting web 115, and connected at the base of the overflow stand pipe 120.

From the above description, it will be apparent that I have provided a bathroom ensemble which 10 does not obstruct either the walls or floor of the bathroom, and in which all of the piping connections and waste connections are concealed from view. Further, I provide a construction which is adapted for use either with right or 15 left hand water supply connections, and which may be selectively changed to suit the particular application for which the tub is employed. Further, by the provision of the longitudinally extending dovetail grooves 64, and by reason of the 20 oppositely threaded ends of the waste pipes 58 and 83, the roughing in operations are considerably reduced, and the space necessary for such operations is correspondingly reduced.

By the elimination of the unsightly and un- 25 sanitary piping connections, as well as the elimination of the floor supports for the lavatory and water-closet, I am able to provide a compact, neat appearing and sanitary type of bathroom plumbing fixture or ensemble, which is 30 capable of being maintained clean and sanitary, and in which the cleaning is facilitated by the elimination of the obstructions on the floors and walls and around the piping connections.

It is obvious that changes, both in the design 35 and construction of the present invention may be provided, without, however, departing from the underlying basic features thereof, and I do not intend to be limited to the exact construction disclosed and described, except as defined 40 by the scope and spirit of the appended claims.

I claim:

1. In combination, a bath tub having an outer front wall and an inner front wall in proximity thereto, a water-closet mounted in raised position on said outer front wall, a lavatory mounted in raised position on said outer front wall, and plumbing connections for said water-closet and lavatory disposed behind said outer front wall and between said outer and inner front walls. 50

2. A plumbing fixture comprising a bathtub having an outer front wall, a water-closet and a lavatory supported in position on said outer front wall, means extending behind said outer front wall for supplying flushing water and hot 55 and cold water to said water-closet and lavatory, respectively, and an imperforate inner front wall disposed inwardly of said last means.

3. In combination, a bathtub having an imperforate inner wall having a front portion and an outer front wall in proximity thereto, a lavatory supported on said outer front wall, hot water connections for said tub and lavatory, cold water connections therefor, said connections being disposed behind said outer front wall and externally 65 of the inner wall of the tub, and a common waste connection for said tub and lavatory.

4. In combination, a bathtub having a front wall, said wall having spaced sets of corresponding openings therein, each of said sets of openings being adapted to receive selectively supporting and piping connections for a water-closet and a lavatory for mounting and connecting the water closet and lavatory each in either of two positions on the front wall of the tub, and means for 75

effecting supply connection to all of said piping connections from one end of said bathtub.

5. In combination, a bathtub having an inner front wall and an outer front wall, a water-closet, a lavatory, said water-closet and lavatory being mounted on the outer front wall of said tub, waste connections extending between the outer and inner front walls of said tub and connected to a waste riser at one side of said tub, individual vent pipes at each of said waste connections, a common vent fitting connected to said individual vent pipes, and means for connecting said fitting to said waste riser.

6. In combination, a tub member having a front wall, a water-closet directly supported on said wall, a waste outlet for said closet extending through said wall, a common waste connection for said tub and said closet, means including a waste pipe having oppositely threaded ends adapted to be connected between said outlet and said common waste connection, and vent means for the tub and water-closet.

7. In combination, a tub member having a front wall, a lavatory directly supported in raised position on said wall, a waste outlet for said tub member, a waste outlet for said lavatory, a common waste connection for both said outlets, and means including a pipe having oppositely threaded ends connected between said lavatory waste outlet and said common waste connection, and vent means for the tub and lavatory.

8. In combination, a tub member having a front wall, a water-closet directly supported on said wall, a lavatory directly supported on said wall and spaced from said closet, separate waste outlet means for said tub member, water-closet and lavatory, a common waste connection receiving waste from all of said outlet means, separate waste connections between said common waste connection and the outlet means of said closet and lavatory, and vent means for the tub, water-closet and lavatory.

9. In combination, a tub member having a front wall, a water-closet directly supported on said wall, a lavatory directly supported on said wall and spaced from said closet, separate waste outlet means for said tub member, water-closet and lavatory, a common waste connection receiving waste from all of said outlet means, separate waste connections between said common waste connection and the outlet means of said closet and lavatory comprising pipes having oppositely threaded ends connected between said waste outlet means and said common waste connection, and vent means for the tub, water-closet and lavatory.

10. A combination ensemble for a bathroom comprising a tub member having a front wall, a water-closet supported solely by said wall, a lavatory having supporting means bolted to said wall, and plumbing connections for said tub, water-closet and lavatory disposed in the rear of said wall and having connections to said tub, water-closet and lavatory concealed by the wall structure of the tub.

11. A combination ensemble for a bathroom comprising a tub member having a front wall extending downwardly to the floor of said room, a water-closet directly supported on said wall above said floor, and a lavatory directly mounted on said wall above said floor, said lavatory and water-closet having piping connections disposed in position beneath the top of said tub member and concealed by the wall structure of the tub.

12. A combination ensemble for a bathroom

comprising a tub member having an integral front wall extending from the rim portion of said tub downwardly to the floor of said room, said wall having spaced sets of openings therein, means engaging said openings for supporting a water-closet in position above said floor upon said wall, and means engaging said openings for supporting a lavatory upon said wall, each of said sets of openings being adapted to receive a means for supporting either a water-closet or a lavatory in position on said wall above the floor of said room.

13. In combination, a bathtub having a substantially planar front wall and a horizontal rim portion, a lavatory having a pedestal engaging the lower surface of the bowl at one end thereof, said pedestal having a vertically extending flange portion at its opposite end, means for bolting said pedestal to said front wall of said tub, and means extending horizontally inwardly from the lower defining edge of said lavatory for securing said lavatory to the rim portion of said tub.

14. In combination, a tub member having an open end portion and a front wall, a lavatory mounted on the outer surface of said wall, a water manifold disposed rearwardly of said wall within the end portion of said tub member, means for supplying hot and cold water thereto, and hot and cold water connections from said manifold extending behind said wall and connected to faucet fixtures at said tub and said lavatory.

15. In combination, a tub member having a recessed tub portion, an integral front wall for said tub member spaced from said recessed portion to provide a piping channel therebetween, a lavatory and a water-closet mounted in spaced relation on said wall, water supply connections for said lavatory and closet extending through said wall into said channel, waste connections therefor extending through said wall into said channel, and piping connections extending through said channel from one end of said tub.

16. In a combination ensemble of the class described, a lavatory comprising a bowl portion and a surrounding peripheral wall portion, a pedestal engaging the outer surface of said bowl within said wall portion, said pedestal terminating in a flange portion at its lower end extending normally to the plane of said lavatory, and means for securing said flange portion to a vertical supporting surface to support said lavatory in position.

17. In combination, a bathtub having a water-closet and a lavatory mounted on the front face thereof, a water manifold having insulated hot and cold water chambers, means for connecting the hot water chamber to faucet fixtures on said tub and lavatory, means for connecting the cold water chamber to said fixtures, and means for connecting one side of said manifold to the flushing chamber of said water-closet, all of said connecting members being disposed entirely within the peripheral extent of said tub and behind said front face thereof.

18. In combination, a waste riser, a bathtub, a water-closet and a lavatory mounted on and entirely supported on the front of said tub, waste connections for said tub, closet and lavatory connected by a common conduit to said riser, and water supply connections for said tub, closet and lavatory, all of said waste connections and supply connections being concealed behind the front of said tub.
